UNITED STATES PATENT OFFICE.

CHARLES A. TATUM, OF NEW YORK, N. Y., ASSIGNOR TO WHITALL, TATUM & CO., OF SAME PLACE.

DESIGN FOR A PILL CYLINDER-MOLD.

SPECIFICATION forming part of Design No. 27,293, dated July 6, 1897.

Application filed May 25, 1897. Serial No. 638,171. Term of patent 14 years.

To all whom it may concern:

Be it known that I, CHARLES A. TATUM, a citizen of the United States, residing in the city, county, and State of New York, have invented and produced a new and original Design for a Pill Cylinder-Mold, of which the following is a specification.

The leading feature of my design is a pill cylinder-mold substantially as shown.

In the accompanying drawings, Figure 1 illustrates a pill cylinder-mold embodying my design, showing the same in side view; and Fig. 2 is a rear view of the same.

In the drawings, *a* is a pill cylinder-mold, apertured, as at *b*, having a banded edge *c*. 15 On one end of the mold the aperture is surrounded by a circle *d* and the other end of the mold is colleted, as at *e*.

What I claim is—

The design for a pill cylinder-mold, substantially as shown. 20

CHARLES A. TATUM.
